COPYHOLDER

Harry Malcolm, Lombard, Ill.

Application July 20, 1928. Serial No. 294,165

16 Claims. (Cl. 120—32)

This invention relates to certain new and useful improvements in copyholders, and more particularly to a device for holding and displaying in a convenient position for transcribing the notes 5 thereon, a strip of paper such as is used in a stenotype machine or similar stenographic type-writing machine. It also relates to means for advancing the sheet through the mechanism so as to expose the notes to be transcribed in certain 10 predetermined positions on the copyholder.

In a stenotype machine, the stenographic notes are mechanically written in a continuous column of words or phrases on a long, comparatively narrow, strip of paper. When the notes are transcribed, this strip should be held in a substantially upright position and advanced upwardly at frequent intervals in order to bring new portions of the notes into view. The paper strip is often quite long and is usually folded into a stack of 15 alternately directed folds, or rolled on spools or cylinders, so that it is difficult when using an ordinary stand or copyholder to successively expose the different portions of the notes to view without frequent handling of the strip and great loss 20 of time.

The principal object of the present invention is to provide an improved copyholder, such as is briefly referred to above, and disclosed more in detail in the description which follows, which will 25 conveniently hold and display the strip of notes, and which is adapted to advance the strip by predetermined steps with little effort on the part of the operator. The device is so arranged that the typist's hands always remain close to the typewriter keys, and a single impulse imparted to an 30 operating key or lever suffices to advance the strip a pre-determined distance.

One object of the invention is to provide simple and easily operated means for advancing the 35 sheet through the copyholder and ejecting it therefrom, without the necessity of previously rolling the strip on spools or other devices.

Another object is to provide means for moving any given portion of the paper strip from one 40 specific point on the display stand to another so that the typist does not lose his place and rapid reading of the notes is facilitated.

Another object is to provide a device of this type into which the strip may be quickly inserted 45 or from which it may be quickly withdrawn so that any desired portion of the strip may be displayed without the necessity of passing the remainder of the strip through the apparatus.

Another object is to provide a copyholder in 50 which the strip may be quickly reversed or turned over so that notes on either side of the strip may be transcribed.

Another object is to provide a device of this 55 type which may be quickly erected for use, or folded into a small and compact form so that it

will occupy very little space when stored away or when carried in a traveling bag.

Another object is to provide a device which is simple, consists of very few parts, and is readily assembled, so that it is economical of manufacture.

Another object is to provide a copyholder of this type capable of supporting and displaying ordinary sheets of paper, books, or other matter to be copied, it being immaterial when so used 70 whether a strip of stenotype paper is positioned in the machine or not.

Another object is the provision of a copyholder in which the strip of notes remains stationary while the notes are being transcribed, thus eliminating blurring of notes, and which is shifted from one pre-determined position on the display stand to another at each operation of the shifting key or lever so that the position of the notes to be transcribed is always known with certainty by the operator.

Other objects and advantages of this invention will be more apparent from the following detailed description of one approved form of apparatus involving the principles of this invention.

In the accompanying drawings:

Fig. 1 is a perspective view of the assembled device when in use.

Fig. 2 is a vertical section, taken substantially on the line 2—2 of Fig. 1.

Fig. 3 is a side elevation of the copyholder when not in use and folded for storage purposes.

Fig. 4 is a section, on an enlarged scale, taken substantially on the line 4—4 of Fig. 2.

Fig. 5 is a transverse section, taken substantially on the line 5—5 of Fig. 4.

Fig. 6 is an end elevation of the ratchet mechanism and friction retarder, the view being taken substantially on the line 6—6 of Fig. 4.

The supporting frame consists of a front display panel A, a casing B supported at the upper end of panel A, a base plate C, and a rear panel D pivotally connecting the rear end of base C 100 with the casing B.

The casing B, which may be built up of suitable metal parts or made in the form of a single casting, comprises side plates 1 and 2, connected at their lower ends by a transverse web 3. A front wall portion 4 and a similar parallel rear wall 5 project downwardly from the web 3 and the lower ends of side walls 1 and 2.

A transverse top member 6, made preferably of arcuate cross section as shown, connects the upper ends of the side walls 1 and 2. A substantially vertical web 7 extends inwardly from the central portion of side wall 1 and connects the top 6 with the lower web 3. This web 7 serves as a guide for the sliding rack 8, hereinafter more fully described, and also serves to strengthen the side wall 1 which supports the upper por- 115 120

tion of the casing. The side wall 2 is slotted from front to rear at 9 so as to divide this wall into a lower portion 10 and an upper portion 11, for reasons hereinafter described.

5 The front display panel A, which is adapted to support that portion of the paper strip from which the notes are to be transcribed, is conveniently formed of a flat sheet metal member strengthened by rearwardly projecting side flanges 12. The upper end of panel A is secured to the front wall 4 of casing B by means of screws 13 or other equivalent fastening means. The lower end of panel A is slotted or cut away as indicated at 14 to provide an opening extending 10 through the lower end of the panel and slightly wider than the paper strip, indicated at 15. A pair of clips or guide members 16, secured to the panel A somewhat above the opening 14, project toward one another so as to overlap the edge 15 portions of the paper strip. These guides hold the strip against the face of the panel and prevent lateral movement thereof without interfering with its vertical travel. A pair of similar guides 17 are positioned adjacent the upper end 20 of panel A.

At a suitable location adjacent the lower end of panel A the face of the panel is provided with one or more index marks or pointers 18 at either side of the path of strip 15, and a similar pair 30 of index marks 19 is placed adjacent the upper end of the panel. The index marks 18 and 19 are spaced apart the exact distance that the strip 15 will be advanced by each movement of the shift key 53. The mechanism may be so proportioned that this distance will be substantially equal to 100 words of copy, or any other convenient division of the notes to be transcribed. A vertical slot 22 is formed in one of the lower side portions of panel A, through which projects 40 the operating key or lever hereinafter described.

The base C and the rear panel D may conveniently be formed of sheet metal plates, similar to the front panel A, and provided with strengthening side ribs or flanges 23 and 24. The front end of base C is provided with an upwardly extending flange 25 by which the lower end 45 of display panel A is engaged when the copyholder is erected for use. The rear end of base C is provided with an upwardly projecting flange 26 which is hinged in any convenient manner as indicated at 27 to the lower end of the rear panel D. Rear panel D is similarly hinged at 28 to the lower end of rear wall 5 of casing B.

Suitable bosses or legs 20 may be stamped from 55 or secured to the bottom of base C for supporting the copyholder on a table or other means of support. It will be noted that when the copyholder is erected for use, as shown in Figs. 1 and 2, the front and rear panels A and D diverge downwardly from the upper casing B and are secured to and braced by the supporting base C so that the copyholder resembles an easel with the front display panel A in a substantially upright position, slightly inclined to the rear, so that the notes 60 on the paper strip are in the most convenient position to be read by the operator.

When the device is not in use, the front panel A may be detached from base C by slightly lifting the same to disengage its lower end from the lip 70 or flange 25, after which base C may be folded in against the rear panel D and the base C and panel D are then folded forwardly against the front panel A, as shown in Fig. 3. The aggregate thickness of the panels A, C, and D, and the mechanism mounted on the back of panel A, is

no greater than the thickness of the casing B, so that a very compact assembly of the parts is obtained when thus folded.

A shaft 29 is rotatably mounted in the side walls 1 and 2 of casing B, above the transverse web 3. Thickened portions or bosses 30 and 31 may be formed on the side walls 1 and 2, in which shaft 29 is journaled. A small pinion 32 is keyed in any convenient manner as indicated at 33 to the shaft 29 adjacent the side wall 1. In a similar manner a ratchet wheel 34 is keyed at 35 to shaft 29 adjacent the side wall 2. The pinion 32 and ratchet wheel 34 serve to hold the shaft 29 against endwise movement through the bearings 30 and 31. Suitable knobs or handles 36 are secured to the respective ends of shaft 29, at the sides of casing B.

80 A roller 37 for frictionally engaging the paper strip 15 is freely rotatable on shaft 29 between the pinion and ratchet wheel. This roller may be constructed in any suitable manner, but is here shown as formed of an inner brass tube 38 journaled on the shaft 29 and metallic end discs 39 and 40 secured to the ends of tube 38 and carrying a hollow spool 41, formed of wood or other suitable material. A tubular soft rubber covering 42, for frictionally engaging the paper sheet, is mounted on the outer cylindrical surface of the spool 41. It will be noted that roller 37 resembles in its general construction the platen 190 of a typewriter, although the covering 42 preferably has a relatively soft surface for insuring a strong frictional grip on the paper sheet.

95 A pawl 43, pivoted at 44 to the end disc 40 of the roller is held yieldably in engagement with the ratchet wheel 34 by means of a suitable spring 45. It will be apparent that when the shaft 29 is rotated in a clockwise direction, as seen from the right of Figs. 1 and 2, or in a counter-clockwise direction, as seen in Fig. 6, the ratchet teeth 105 115 will engage the pawl 43 and cause roller 37 to rotate with the shaft. However, when the shaft 29 is rotated in the reverse direction, the spring 45 will yield, permitting the pawl 43 to ride over the ratchet teeth so that no rotation of the roller 120 125 in the reverse direction will take place.

A suitable friction retarder 46, pivoted at one end 70 on the fixed side wall 2, is constantly held in frictional engagement with an out-turned flange 47 on the periphery of disc 40 by the spring 135 71 interposed between retarder 46 and the web 3. This serves to prevent over-running of the roller 37 when the first rotation of shaft 29 in the counter-clockwise direction (Fig. 6) is suddenly halted, and serves to hold the roller against rotation when shaft 29 is rotated in a clockwise direction.

130 The rack 8, already referred to, meshes with the pinion 32 and is interposed between the pinion and the web 7 in casing B so as to be constantly held in engagement with the pinion teeth. The rack is guided for vertical movement in a slot 72 in web 7 and passes through openings 48 and 49 in the web 3 and top 6 respectively. This rack 8 is formed on the upper portion of a bar 50 140 which is slidably guided near its lower end in a suitable guide bracket 51 projecting from the rear face of panel A. The lower end of bar 50 is formed with a right-angle extension 52 which projects outwardly through the slot 22 in the 145 display panel. A suitable key or handle 53 is hinged at 54 to the end of the bar extension 52, adjacent the front face of panel A. A finger 73 on the rear end of key 53 engages the underside of bar extension 52 so as to hold the key 53 in 150

alignment with the bar 52 when downward pressure is applied to the key, but the key may be folded upwardly against the face of panel A when the device is not in use, as shown in Fig. 3. A 5 tension spring 55 is secured at its lower end to the bar extension 52, and is anchored at its upper end to a bracket 56, formed on the inner face of the front wall 4 of casing B. This spring 55 normally serves to hold the bar 50 and rack 8 in 10 their extreme upper positions, this upward movement being limited by the engagement of the bar extension 52 with the upper end of slot 22. The downward movement of the rack is limited by the engagement of bar extension 52 with the 15 lower end of slot 22.

A substantially U-shaped frame 57, comprising a pair of side lever arms 58 and 59, is pivoted at 60 between the rear upper portions of the side walls 1 and 2 of casing B. A shaft 20 61, mounted in the forward portions of the levers 58 and 59, (Fig. 4), carries a freely rotatable roller 62 provided with a rubber covering 63 similar to that on the main roller 37. A 25 pair of compression springs 64 and 65 are confined between the respective levers 58 and 59 and the top member 6 of the casing so as to yieldably hold the roller 62 against the roll 37, or against the paper strip 15 when interposed between the rollers. By lifting up on either of the handle extensions 66 provided at the outer ends of the 30 levers 58 and 59, roller 62 may be temporarily lifted out of engagement with the main roller 37, against the resistance of the springs 64 and 65.

35 A pair of spring clips 67 are secured by screws 13 or in any other suitable manner to the upper portion of panel A, one at either side of the path of the paper strip 15. These clips may be utilized, either singly or together, to hold any 40 loose sheets or papers of copy against the display panel A.

When the copyholder is to be set up for use, the base C and rear wall D are folded out as shown in Figs. 1 and 2 and the display panel A 45 inserted at its lower end behind the flange 25 on the base. The upper end of the paper strip 15 is passed from the rear through opening 14 in the display panel, then threaded upwardly behind the guides 16 and 17 and inserted between the friction rollers 37 and 62 which may be given 50 a partial rotation to draw the strip between the rollers, either by depressing the key 53 or by turning one of the knobs 36 at the ends of shaft 29. Roller 37 will be rotated until the 55 beginning of the copy that is to be transcribed is substantially opposite the index marks 19 at the top of panel A. The operator now transcribes the notes in the usual manner and when he has read to a position substantially opposite the lower 60 indexes 18 the key 53 will be given a single downward stroke or impulse until the bar 52 engages the bottom of slot 22, at which time the key is released and will be returned to its initial position by the spring 55. During the downward 65 stroke of the key and rack, the shaft 29 will be rotated in a counter-clockwise direction as seen in Fig. 6 and will carry the roller 37 with it since the ratchet 34 engages with pawl 43. The strip 15 will be gripped frictionally between the rollers 37 and 62 and drawn upwardly and ejected through the rear of casing B. The parts are so 70 proportioned that the strip will be drawn upwardly a distance just equal to the distance between the index marks 18 and 19 so that the notes last transcribed opposite index 18 will now

be located opposite the upper index marks 19. The operator will now know exactly where to find the notes next to be transcribed and no time will be lost. The main body of the strip 15 which is to be transcribed (which may be either 80 in the form of a stack of alternately folded sections as shown in the drawings or in the form of a roll), is laid upon the base member C between the front and rear panels and will automatically feed itself through the opening 14 and upward between the guides 18 and 19 along the face of display panel A. If desired, an idler roll 69 may be mounted in panel A, at the upper edge of opening 14, to facilitate the passage of the paper strip through this opening. If extra long 85 "takes", or lengths of paper strip are to be transcribed, the pad or roll of notes may be placed on the floor or table and passed up behind guides 16 instead of being placed on the base panel C. After the strip is ejected from the rear of casing B it may be caught in any suitable receptacle or 90 permitted to fold itself upon the table or floor at the rear of the copyholder.

In case the operator desires to transcribe notes 95 from an intermediate portion of a long strip of 100 copy, it is not necessary to run the entire strip through the device, but the portion of the strip just above that portion which the operator desires to expose to view may be passed sidewise through slot 9 in the side of casing B and between 105 the rollers 37 and 62, the upper roller 62 being elevated to permit the insertion of the strip by lifting up on one or both of the handles 66. The lower end of panel A is raised to permit the 110 lower portion of strip 15 to be passed upwardly through the bottom of opening 14 and the remainder of the strip is laid as before upon the base member C, the lower end of panel A then being returned to its normal position behind the flange 25 on the base. The key 53 is now manipulated 115 in the usual manner to advance the strip upwardly by pre-determined steps until the end of the matter to be transcribed is reached, at which time the entire strip may be removed sidewise from the machine by a reversal of the operations just described.

When a stenotypist prints three stars (or other suitable indication of an error), it signifies that the matter immediately preceding should be changed to read as rewritten following the 125 stars. Since the display panel A is quite long and displays approximately one hundred words at one time, the danger of copying notes that must subsequently be canceled is greatly diminished.

If the operator desires to use the display stand for holding loose sheets of copy, or other similar matter, the sheets may be inserted under the spring clips 67, or may be inserted behind the flange 25 of the base and resting against 135 the panel A. If necessary, the key 53 may be folded back against the panel A so as not to interfere with the wider sheets. The copyholder may be used in this manner without the necessity of removing any stenotype strip or roll that is already in place within the holder. If a book is to be supported, the panel A may be moved back to provide a supporting space for the thicker object between the panel and flange 25.

When not in use, the device may be quickly collapsed by simply folding in the base and rear panels, as already described, and folding up the key 53. This is but the work of an instant, and the device may now be stored away in a 145

drawer or other small receptacle, or easily carried in a traveling case.

It will be obvious that either side of a strip of notes may be exposed in this copyholder, it being a very simple operation to remove and reverse the strip.

Since the various makes of typewriters employ both right and left-hand carriage return levers, the spacing lever or key on the copyholder 10 may be placed on either the right or left side of the front panel. It will be noted that the major portion of the space between the front and rear panels of the copyholders is entirely open and unobstructed so that the copyholder may be positioned closely adjacent either side of the typewriter, with the typewriter carriage projecting 15 between the panels and freely movable in this space. This will bring the notes into the most convenient position for reading and place the 20 shifting key or lever of the copyholder in a position where it may be operated with a minimum of effort.

The copyholder may be conveniently and economically formed of metal stampings and castings, but it will be apparent that many portions 25 of the device could be formed of wood or other materials. While the rack and pinion mechanism here disclosed is one approved example of a suitable mechanism for imparting rotation to 30 the roller shaft, other forms of gearing such as sprocket chain and sprocket, or a cable and drum could be substituted, and it is to be understood that all such equivalent mechanisms are considered as within the scope of the invention as defined by the following claims.

I claim:

1. In a device of the character described, a supporting stand comprising a substantially upright long display panel of sufficient length to 40 display a page of matter at one time, guiding means positioned adjacent the top and bottom of the panel for holding a paper copy strip against the panel but permitting upward movement of the strip thereover, marks adjacent the 45 top and bottom of the panel respectively for designating the upper and lower limits of the copy to be transcribed, a pair of friction rollers mounted in the stand adjacent the upper end of the panel, one side of the stand being slotted to permit the insertion between the rollers of an 50 intermediate portion of a continuous strip, means for yieldingly urging one roller toward the other to frictionally grip the strip therebetween, and manually actuated mechanism connected with one of the rollers and adapted at 55 each actuation to impart sufficient rotation to the roller to advance a point on the strip from the lower mark to the upper mark.

2. In a device of the character described, a 60 supporting stand comprising a substantially upright display panel of sufficient length to display a page of matter at one time, guiding means positioned adjacent the top and bottom of the panel for holding a paper copy strip against the 65 panel but permitting upward movement of the strip thereover, a shaft rotatably mounted in the stand adjacent the upper end of the panel, a roller journaled on the shaft, a one-way clutch connecting the roller and shaft, a second roller 70 mounted in the stand for free rotation, means for yieldably urging the second roller toward the first roller so as to frictionally grip the strip therebetween, a pinion on the shaft, a rack meshing with the pinion and guided in the stand for 75 longitudinal reciprocation, a spring for moving

the rack in one direction, one side of the stand being slotted to permit the insertion between the rollers of an intermediate portion of a continuous strip, and manually operable means for imparting a predetermined longitudinal movement to the rack in the opposite direction to advance the lowermost portion of the strip to the uppermost portion of the panel.

3. A copyholder comprising a display panel of sufficient length to display a page of matter at one time, guides on the panel for a paper copy strip, a casing mounted at the upper end of the panel projecting rearwardly thereof, means mounted in and extending from the casing for advancing the strip upwardly through the guides approximately the length of the panel and passing and ejecting the strip through and from the casing, one side of the casing being slotted to permit the insertion in the advancing means of an intermediate portion of a continuous strip, and means for supporting the panel in upright position, said means being foldable against the rear face of the panel and in substantial alignment with the casing.

4. A copyholder comprising a display panel of sufficient length to display a page of matter at one time, guides on the panel for a paper copy strip, a casing mounted at the upper end of the panel and projecting to the rear thereof, means mounted in and extending from the casing for advancing the strip upwardly through the guides approximately the length of the panel and passing and ejecting the strip through and from the casing, one side of the casing being slotted to permit the insertion in the advancing means of an intermediate portion of a continuous strip, a base plate formed at one end to detachably engage the lower end of the panel, and a rear supporting plate hinged at its upper end to the rear edge of the casing and at its lower end to the base plate, the rear plate and base plate being foldable into substantial parallelism with the panel and in alignment with the casing.

5. A copyholder comprising a long display panel, guides on the panel for a paper copy strip, a casing mounted at the upper end of the panel and projecting to the rear thereof, means mounted in and extending from the casing for advancing the strip upwardly through the guides approximately the length of the panel, one side of the casing being slotted to permit the insertion in the advancing means of an intermediate portion of a continuous strip, a base plate having an upturned flange at its front end behind which the lower end of the display panel is detachably engaged, and a rear panel hinged at its upper end to the rear edge of the casing and at its lower end to the base plate, the rear panel and base plate being foldable into substantial parallelism with the display panel.

6. A copyholder comprising a long display panel, means on the front face thereof for guiding a paper strip for upward movement from the bottom to the top of the panel, a casing mounted at the upper end of the panel, a shaft journaled in the casing, a roller rotatably mounted on the shaft, a one-way clutch connecting the shaft and roller, a pinion on the shaft, a rack-bar guided for vertical movement in the casing and meshing with the pinion, a spring for urging the rack upwardly, there being a slot in the lower portion of the display panel, the lower end of the rack-bar having an extension projecting through the slot, a manually operable key mounted on the bar extension for depressing the

rack, a movable frame rotatably mounted in the casing, a roller carried by the frame, springs for rotating the frame to carry the roller therein into yielding engagement with the first named roller, one side of the casing being slotted to permit the insertion between the rollers of an intermediate portion of a continuous strip and means for supporting the panel in display position.

7. A copyholder comprising a display panel of sufficient length to display a page of matter at one time, means on the front face thereof for guiding a paper strip for upward movement over the panel a distance approximately the length of the panel, a casing mounted at the upper end of the panel, a shaft journaled in the casing, a roller rotatably mounted on the shaft, a one-way clutch connecting the shaft and roller, a pinion on the shaft, a rack-bar guided for vertical movement in the casing and meshing with the pinion, a spring for urging the rack upwardly, there being a slot in the lower portion of the display panel, the lower end of the rack-bar having an extension projecting through the slot, a manually operable key mounted on the bar extension for depressing the rack, a movable frame rotatably mounted in the casing, a roller carried by the frame, springs for rotating the frame to carry the roller therein into yielding engagement with the first named roller, one side of the casing being slotted to permit the insertion between the rollers of an intermediate portion of a continuous paper strip, the lower end of the display panel being slotted to permit the passage of the paper strip therethrough, and means for supporting the panel in display position.

8. A copyholder comprising a display panel of sufficient length to display a page of matter at one time, means on the front face thereof for guiding a paper strip for upward movement over the panel a distance approximately the length of the panel, a casing mounted at the upper end of the panel, a shaft journaled in the casing, a roller rotatably mounted on the shaft, a one-way clutch connecting the shaft and roller, a pinion on the shaft, a rack-bar guided for vertical movement in the casing and meshing with the pinion, a spring for urging the rack upwardly, there being a slot in the lower portion of the display panel, the lower end of the rack-bar having an extension projecting through the slot, a manually operable key pivotally mounted on the bar extension and normally projecting outwardly in position to be depressed for lowering the rack, the key being foldable upwardly into substantial parallelism with the display panel, a second roller movably mounted in the casing, springs for urging this roller into yielding engagement with the first named roller, one side of the casing being slotted to permit the insertion between the rollers of an intermediate portion of a continuous strip, and means foldable into substantial parallelism with the panel for supporting the panel in display position.

9. A copyholder comprising a long display panel, guides on the panel for a paper copy strip, a casing mounted at the upper end of the panel and projecting to the rear thereof, means mounted in and extending from the casing for advancing the strip upwardly through the guides a distance approximately the length of the panel at each actuation and passing and ejecting the strip through and from the casing, one side of the casing being slotted to permit the insertion in the advancing means of an intermediate portion of a continuous strip, said means being

mounted at the rear of the panel and having an arm projecting forwardly through the panel for actuating the advancing means in the casing, a manually operable key pivoted to the arm and foldable against the front of the casing, and means for supporting the panel pivotally connected with the casing and foldable into substantial alignment therewith against the rear face of the panel.

10. In a copyholder, comprising a supporting stand, a display panel of sufficient length to display a page of matter at one time, means for guiding a strip for longitudinal movement along the panel, a casing mounted adjacent one end of the panel, a pair of rollers in said casing, one side of the casing being slotted to permit the insertion between the rollers of an intermediate portion of a continuous strip, means for yieldingly urging one of the rollers toward the other so as to grip the strip therebetween, and means for advancing the strip a predetermined distance approximately the length of the panel, including a shaft on which one of the rollers is rotatably mounted, a one-way clutch for connecting the shaft and roller, a pinion on the shaft, a rack engaging the pinion and guided for reciprocation in the supporting stand, and manually operable means for moving the rack.

11. In a copyholder, comprising a supporting stand, a display panel of sufficient length to display a page of matter at one time, means for guiding a strip for longitudinal movement along the panel, a casing mounted adjacent one end of the panel, a pair of rollers in said casing, one side of the casing being slotted to permit the insertion between the rollers of an intermediate portion of a continuous strip, means for yieldingly urging one of the rollers toward the other so as to grip the strip therebetween, and means for advancing the strip a predetermined distance approximately the length of the panel, including a shaft on which one of the rollers is rotatably mounted, a one-way clutch connecting the shaft and roller, a pinion on the shaft, a rack engaging the pinion and guided for reciprocation in the supporting stand, manually operable means for moving the rack in one direction, and a spring for returning the rack to its original position.

12. In a copyholder, comprising a supporting stand, a display panel of sufficient length to display a page of matter at one time, means for guiding a strip for longitudinal movement along the panel, a casing mounted adjacent one end of the panel, a pair of rollers in said casing, one side of the casing being slotted to permit the insertion between the rollers of an intermediate portion of a continuous strip, means for yieldingly urging one of the rollers toward the other so as to grip the strip therebetween, and means for advancing the strip a predetermined distance approximately the length of the panel, including a shaft on which one of the rollers is rotatably mounted, a one-way clutch connecting the shaft and roller, a pinion on the shaft, a rack engaging the pinion and guided for reciprocation in the supporting stand, a retarder mounted on the supporting stand and frictionally engaging the rotatably mounted roller, manually operable means for moving the rack in one direction, and a spring for returning the rack to its original position.

13. In a copyholder, a supporting stand comprising a display panel, a casing mounted adjacent one end of the panel, a pair of rollers in said casing, one side of the casing being slotted

to permit the insertion between the rollers of an intermediate portion of a continuous strip, means for guiding a paper strip for longitudinal movement along the panel, means for yieldingly urging one of the rollers toward the other so as to grip the strip therebetween, and means for rotating one of the rollers more than one revolution.

14. A copyholder comprising a display panel, 10 means on the front face thereof for guiding a paper strip for upward movement over the panel, a casing mounted at the upper end of the panel, a shaft journaled in the casing, a roller rotatably mounted on the shaft, a one-way clutch connecting the shaft and roller, a pinion on the shaft, a rack-bar guided for vertical movement in the casing and meshing with the pinion, a spring for urging the rack upwardly, there being a slot in the lower portion of the display panel, the 15 lower end of the rack-bar having an extension projecting through the slot, a manually operable key mounted on the bar extension for depressing the rack, a movable frame mounted in the casing, a roller carried by the frame, springs for moving the frame to carry the roller therein into yielding engagement with the first named roller, one side of the casing being slotted to permit the insertion between the rollers of an intermediate portion of a continuous paper strip, the lower end of the display panel being slotted to permit the passage of the paper strip therethrough, a base plate having its front end detachably engaged with the lower end of the display panel, and a rear supporting panel hinged at its upper and lower ends to the casing and the rear end of the base respectively. 20

15. A copyholder comprising a display panel, 30 means on the front face thereof for guiding a paper strip for upward movement over the panel, a casing mounted at the upper end of the panel, a shaft journaled in the casing, a roller rotatably mounted on the shaft, a one-way clutch connecting the shaft and roller, a pinion on the shaft, a rack-bar guided for vertical movement in the casing and meshing with the pinion, a spring for urging the rack upwardly, there being a slot in the lower portion of the display panel, the 35 lower end of the rack-bar having an extension projecting through the slot, a manually operable key pivotally mounted on the bar extension and normally projecting outwardly in position to be depressed for lowering the rack, the key being foldable upwardly into substantial parallelism with the display panel, a second roller movably mounted in the casing, springs for urging this 40 roller into yielding engagement with the first named roller, a base plate formed at its front end to detachably engage and support the lower end of the display panel, and a rear panel hinged at its upper and lower ends to the casing and the rear end of the base respectively. 45

sion projecting through the slot, a manually operable key mounted on the bar extension for depressing the rack, a movable frame mounted in the casing, a roller carried by the frame, springs for moving the frame to carry the roller therein into yielding engagement with the first named roller, one side of the casing being slotted to permit the insertion between the rollers of an intermediate portion of a continuous paper strip, the lower end of the display panel being slotted to permit the passage of the paper strip therethrough, a base plate having its front end detachably engaged with the lower end of the display panel, and a rear supporting panel hinged at its upper and lower ends to the casing and the rear end of the base respectively. 80

16. A copyholder comprising a display panel, 85 means on the front face thereof for guiding a paper strip for upward movement over the panel, a casing mounted at the upper end of the panel, a shaft journaled in the casing, a roller rotatably mounted on the shaft, a one-way clutch connecting the shaft and roller, a pinion on the shaft, a rack-bar guided for vertical movement in the casing and meshing with the pinion, a spring for 90 urging the rack upwardly, there being a slot in the lower portion of the display panel, the lower end of the rack-bar having an extension projecting through the slot, a manually operable key pivotally mounted on the bar extension and normally projecting outwardly in position to be depressed for lowering the rack, the key being foldable upwardly into substantial parallelism with the display panel, a second roller movably mounted in the casing, springs for urging this 95 roller into yielding engagement with the first named roller, a base plate formed at its front end to detachably engage and support the lower end of the display panel, and a rear panel hinged at its upper and lower ends to the casing and the rear end of the base respectively. 100
